PIEZOELECTRIC APPARATUS

Alfred L. W. Williams, Cleveland Heights, Ohio,
assignor to The Brush Development Company,
Cleveland, Ohio, a corporation of Ohio.

Application November 14, 1938, Serial No. 240,261

8 Claims. (Cl. 171—327)

This invention relates to piezo-electric apparatus and more particularly to means for supporting flexing type piezo-electric units.

An object of this invention is to provide means for supporting piezo-electric units which means permits a high degree of freedom for flexure of the unit while preventing motion of the supported portions of the unit normal to its faces.

Piezo-electric units of the flexing type are now well known in the art. Briefly they comprise a plurality of plates of piezo-electric material such as Rochelle salt crystal cemented together face to face and so oriented that the assembly either bends or twists an application of a difference of potential between its electrodes and conversely develops a difference of potential between its electrodes when it is bent or twisted. The one type is called a bending unit and the other type a twisting or torque unit. For a detailed description of such units reference may be made to the following United States Patents: Re. 20,213 and Re. 20,680 issued December 22, 1936, and March 29, 1938, respectively, to C. B. Sawyer, and 2,105,011 issued January 11, 1938, to A. L. W. Williams.

Piezo-electric units are used as electro-mechanical energy converters in a variety of devices such as microphones, loud speakers, oscillographs and vibration measuring devices. When the forces applied to or delivered by the piezo-electric unit are not great, the unit is commonly supported at a plurality of points between yielding pads of material such as rubber. Such supports permit flexing of the unit without serious lost motion of the supported portions in a direction perpendicular to the faces of the unit. When relatively great forces are involved, the yielding pads have been replaced by metal plates cemented to the unit and each having a hemispherical projection engaging a flat surface of the crystal unit housing. This form of mounting holds the supported parts of the unit rigidly against movement normal to the faces of the unit. Both of the above types of supports are fully described in United States Patent 2,105,011.

It has been found that in some devices involving large forces the above rigid type of mounting is unsatisfactory. When the unit flexes the projecting parts of the metal plate supports slide over the contacting surface. The friction at these points introduces undesirable effects. For example, in the direct ink writing oscillograph described in United States Patent No. 2,149,216 issued February 28, 1939 to Charles K. Gravley, the pen point does not always return to its normal position after an actuating charge has been removed from the crystal unit. This gives rise to false records of the applied electrical waves.

In the preferred form of the present invention

the crystal unit has cemented to it a flat hardened metal plate at each point of support. Opposite each such plate and parallel thereto is disposed a similar plate supported on a rigid base or frame. Each pair of plates is spaced apart by a metal ball. Pressure members are provided to hold the plates and ball in contact with a pressure greater than the greatest reactionary force on the supports. This arrangement holds the supported areas of the unit rigidly against motion normal to the faces of the unit while permitting a high degree of freedom for flexure of the unit. A yielding retaining ring is provided to hold the ball in place between the hardened plates. It is convenient to assemble separate supporting units each comprising a retaining ring, a ball and a pair of metal plates and then embody the required number of such supporting units in each device. For this purpose the supporting units may be held together by a small amount of cement at the junction of retaining ring and metal plates. The number of support units used in a piezo-electric device will, of course, depend on the type of unit and the mounting required for the desired results.

For the purpose of further illustration the invention will now be described with reference to the accompanying drawing which illustrates such a support unit and a piezo-electric motor or generator device embodying three such support units. In the drawing,

Fig. 1 is a front elevation of an enclosed piezo-electric motor or generator device with some of the parts broken away to show interior construction.

Fig. 2 is a sectional view on the line 2, 2, of Fig. 1.

Fig. 3 is a sectional view on the line 3, 3, of Fig. 1.

Fig. 4 is an enlarged sectional view corresponding to the right hand portion of Fig. 3.

Fig. 5 is an enlarged plan view of the improved supporting unit with a portion of the surface broken away to show the interior construction.

Fig. 6 is an enlarged sectional view of the unit, and

Fig. 7 is an enlarged elevation.

Fig. 8 and 9 are enlarged central sectional views of the supporting unit showing the parts displaced to an exaggerated degree to illustrate their operation.

Fig. 10 is a sectional view of a modification wherein the ring of elastic material engages and is secured to only one bearing plate.

Fig. 11 is a sectional view of another modification wherein the elastic member is omitted.

In Figs. 1, 2 and 3 a square torsion piezo-electric unit 1 of the type disclosed in United

States Patent 2,105,011 is enclosed and supported in a metal housing comprising a cast box 2, cover plate 3 and gaskets 4, 4. The box assembly is held together by screws 5, 5.

The piezo-electric unit comprises four plates 1a, 1b, 1c and 1d of crystalline material such as Rochelle salt. The plates are cut with their faces perpendicular to the electrical axis and their edges parallel to the b and c axes. The plates are secured together face to face with appropriate orientation and are provided with electrodes 6a (in Fig. 4) which are connected to leads 6, 6. A difference of potential applied between leads 6, 6 causes the unit to twist and conversely twisting forces applied to the unit cause a difference of potential to appear between leads 6, 6. The unit is clamped at three corners by supporting means to be described below. To the fourth corner is secured a drive pin 7 which extends through an opening 8a in cover 3. The opening is sealed with a plug of gum rubber 8. Due to the three corner mounting of the unit an endwise force applied to drive rod 7 causes twisting of the unit with resultant appearance of a potential difference between leads 6, 6; conversely a potential difference applied between leads 6, 6 causes the unit to twist with resultant endwise displacement of the drive rod 7.

Motor or generator devices of this type may be used for a variety of purposes. For example, a loud speaker diaphragm or a phonograph stylus may be connected to the drive pin 7. The United States Gravley Patent No. 2,149,216 above referred to discloses a novel motion converting mechanism in combination with a motor device of this type and a light weight pen arm for direct ink recording of electrical waves on a moving strip of paper. In this and some other devices relatively great forces are applied to the crystal unit supports and it is important to prevent lost motion of the supported parts of the unit in a direction normal to its faces. Furthermore, it is desirable that the unit remain entirely free to flex. The above requirements are met by the supports provided by this invention. In the motor generator device illustrated, three supporting units 9, 9 are disposed at three corners on one side of the unit. These units are highly resistant to compression forces but offer very little resistance to flexing or shearing forces as will be described below. Adjacent the other face of the unit and opposite the three supports 9 are disposed resilient members 10, 10 which are held under compression by the metal housing.

Referring now to Figs. 5, 6 and 7, each support unit 9 comprises a pair of hardened metal discs 11, 11 spaced apart by a ball 12 of suitable material, preferably metal. Retaining ring 13 of soft rubber or the like is provided to hold the ball approximately at the center of the assembly. For convenience the retaining ring 13 may be cemented to the discs 11 to provide a complete supporting unit. In the motor generator device illustrated, each support unit 9 has one metal disc 11 cemented to a thin plate 14 of insulating material such as Bakelite which in turn is cemented to a face of the crystal unit 1. The other disc 11 of each support engages the cover plate 3. A resilient member 10 compressed between the element and cast box opposite each support unit holds the corresponding discs 11 and ball 12 in contact, while pressing the whole assembly firmly against cover 3. The force holding these members in contact is greater than the greatest reactionary force on the sup-

ports and therefore the unit is effectively rigidly supported insofar as forces normal to the faces of the unit are concerned.

Due to the construction of the support units 9 the crystal unit is free to flex. Figs. 8 and 9 are sectional views illustrating the manner in which the support units 9 may distort under the flexing action of the crystal unit. Fig. 8 illustrates the result of a shearing force tending to move the two discs in opposite directions parallel to the planes of the discs. Fig. 9 illustrates a rocking or flexing action. Both illustrations are greatly exaggerated. Actually the support units may partake of a complex motion which is a combination of the motions illustrated in Figs. 8 and 9, and these effects may take place in more than one direction in the same plane. The opening in retaining ring 13 may be larger than the ball to permit maximum freedom of motion. However, it has been found that a close fit makes assembly somewhat easier and does not interfere with the action of the support. This is probably due to the very small motions involved and the yielding nature of the ring. Moreover, the retaining ring may be slightly thicker than the diameter of the ball, since it will be compressed when mounted until the two bearing plates contact the ball.

Obviously the present invention may be modified in various other ways. For example, the retaining ring need not be cemented to the metal discs, the frictional engagement between the parts being relied upon to hold them in place. Alternatively, the retaining ring may be somewhat thinner than the diameter of the ball and may be cemented at one face only to one of the metal discs. This latter construction is illustrated in Fig. 10, in which a pair of metal discs 11a, 11b, are spaced apart by a ball 12a and the ball is yielding held in position by retaining ring 13a which is cemented to metal disc 11a. The above modifications of the supporting unit will produce substantially the same results but are somewhat less convenient to assemble. In fact the retaining ring 14 may be dispensed with entirely in some applications as illustrated in Fig. 11, in which case a small amount of grease may be employed to hold the parts together during assembly or the metal parts may be made of steel and magnetized.

It will be realized that when a ball support of this type is used, very high local stresses may occur in the ball and in the plates which contact it. Unless the plates and ball have quite high values of hardness, deformations may occur in them during use. Naturally, if the ball becomes flattened, or a plate becomes deformed immediately under the ball, the advantages of this type of ball support are largely lost. For this reason, hardened plates are specified herein. The degree of hardness will, of course, be determined by the stresses involved in the structure; with a given load, the stress will increase as the diameter of the ball decreases. Where a large ball may be used to support a small load, it will be obvious that hardened plates may not be required. Furthermore, in such instances it may then be possible and desirable to use some materials other than metal, or to omit the bearing plates and allow the ball to contact the moving member and the supporting case directly.

It will be seen that the supporting unit of this invention permits a freedom of movement in the crystal unit which has not heretofore been at-

tained. Even with the rather complex motion of the supporting corners of a flexing unit such as has been illustrated above, frictional resistance of the supporting unit is reduced to a minimum with the result that a new level of coordination is achieved between the crystal unit and its co-operating elements.

As can be readily appreciated, it is not necessary that a completely spherical ball be used in the mounting here disclosed since in use the member is not rotated as much as 180°. Thus, when used in devices which require only slight rotation of the member, the member could be a body of very irregular shape provided with diametrically opposed spherical surfaces. Furthermore, its spherical surfaces could be of different radii. In view of these conditions, the term "ball-shaped member" is used in the following claims to mean a member of any shape which is provided with two spherical surfaces normal to the same line and having a common center lying between the surfaces.

Having now disclosed the invention, what I claim is:

1. A piezo-electric device comprising a support, a flexing type piezo-electric unit having a pair of substantially parallel faces, anti-friction means disposed between said unit and said support comprising a pair of metal plates disposed substantially in parallelism and spaced apart by a metal ball, the first of said plates engaging a face of said unit and the second of said plates engaging said base, and yielding means disposed adjacent the other face of said unit opposite said first plate and adapted to urge said unit toward said support.

2. A piezoelectric device comprising a flexing type piezoelectric unit; a support therefor; a bearing member between said unit and said support; and cushioning material adapted to press said unit toward said support; said bearing member consisting of a pair of plane bearing plates disposed in substantial parallelism, a single ball-shaped member disposed between said plates in rolling contact therewith, and an annular ring of flexible material encircling the ball-shaped member and secured to a face of at least one of said plates.

3. A device having the combination which consists of: a support having a plane bearing surface thereon; a flexing type piezoelectric unit having a plane bearing surface thereon disposed substantially parallel to the bearing surface of said support and substantially in register therewith, the bearing surface of said piezoelectric unit being subject to limited universal movement relative to the bearing surface of said support with or without concurrent translational movement with respect thereto; and a single ball-shaped member disposed between the said bearing surfaces and in contact with each.

4. A device having the combination which consists of: a support having a plane bearing surface thereon; a flexing type piezoelectric unit having a plane bearing surface thereon disposed substantially parallel to the bearing surface of said support and substantially in register therewith, the bearing surface of said piezoelectric unit being subject to limited universal movement relative to the bearing surface of said support with or without concurrent translational movement with respect thereto; a single ball-shaped member disposed between the said bearing surfaces;

for holding the said bearing surfaces with said ball-shaped member.

5. A device which comprises: a piezoelectric unit which in its inoperative state is substantially flat, a portion which is adapted when in use to curve, a portion and simultaneously to contact a portion; supporting means; bearing means positioned between said supporting means and said crystal unit to provide anti-friction between one of said portions; and means for urging said latter portion of said crystal unit against said bearing means; said bearing means consisting of a ball-shaped member in rolling engagement with a first plane bearing surface on said support and with a second plane bearing surface on said crystal unit, and flexible retaining means encircling said ball-shaped member and spaced outwardly from the portions thereof which make contact with said first and second bearing surfaces.

6. A device which comprises: a four-cornered piezoelectric plate-like assembly which is adapted to flex when in use; supporting means; three bearing assemblies positioned between said support and said piezoelectric assembly at each of three corners of the latter; means for holding said piezoelectric assembly against said three bearing assemblies; and a drive link coupled to the fourth corner of said piezoelectric assembly and subject to movement in a direction substantially perpendicular to the plane of the piezoelectric assembly as the latter flexes, each of said bearing assemblies consisting of a ball-shaped member in rolling engagement with a first plane bearing surface on said support and with a second plane bearing surface on said piezoelectric assembly, and flexible retaining means encircling said ball-shaped member and spaced outwardly from the locations thereon which engage said first and second bearing surfaces, to establish areas for free rolling movement of said ball-shaped member as said piezoelectric assembly flexes.

7. A piezoelectric device comprising: a support; a flexing-type piezoelectric unit having a pair of substantially parallel faces; bearing means between said unit and said support in engagement with one of said substantially parallel faces and with said support; and cushioning means in engagement with the other of said substantially parallel faces for pressing said piezoelectric unit toward said support; said bearing means consisting of: a pair of substantially parallel plane surfaces, and a ball-shaped member disposed between said plane surfaces in rolling contact with each.

8. A magnetic antifriction bearing unit particularly adapted for use between a support and a member which is subject to limited universal rocking movement relative to said support and which may or may not be subject to concurrent translational movement parallel to said support, said unit consisting of: a pair of bodies each provided with a plane bearing surface, said bodies being composed of magnetic material and disposed with their said surfaces in substantial parallelism; and a single ball-shaped member of magnetic material disposed between and in contact with said surfaces, at least one of said three elements of the unit being magnetized to thereby establish magnetic attraction between said ball-shaped member and at least one of said surfaces.
